JAMES K. LANNING, OF BOSTON, MASSACHUSETTS.

WINDING MECHANISM FOR FORMING YARN OR THREAD PACKAGES.

1,141,875.

Specification of Letters Patent.

Patented June 1, 1915.

Application filed August 8, 1912. Serial No. 713,985.

To all whom it may concern:

Be it known that I, JAMES K. LANNING, a citizen of the United States, and a resident of Boston, in the county of Suffolk and 5 State of Massachusetts, have invented an Improvement in Winding Mechanism for Forming Yarn or Thread Packages, of which the following description, in connection with the accompanying drawings, is a 10 specification, like characters on the drawings representing like parts.

This invention relates to winding mechanism for forming yarn or thread packages and specifically and more particularly to 15 builder mechanism for ring spinning or twisting mechanism.

In the application of John V. Cunniff, Serial No. 685,030, filed March 20, 1912, there is disclosed and claimed broadly continuously 20 acting mechanism for winding yarn packages in the general form of cops or bobbins to secure an increase in gain and preferably a progressively increasing gain throughout the formation of the base of the 25 package, preferably with an undiminished gain throughout the balance of the package, and in combination with an increase in traverse throughout the base of the package and preferably throughout the whole package. 30 In such application, the disclosed embodiment of the invention comprises a single acting traverse and gain controlling mechanism having in combination with the yarn receiver and a yarn guide, a primary actuator lever, yarn guide holding means and connecting and governing devices between 35 said lever and said means co-operatively arranged to secure the above results, and in such embodiment the general mechanism provides for the shortening or taking-on 40 of a flexible element which is one element of said connecting and governing devices. In the application of John V. Cunniff, Serial No. 706,910, filed July 1, 1912, there is disclosed 45 mechanism intended to perform the same functions that are fulfilled by the mechanism of the earlier application and wherein the flexible element is let off or elongated during the winding operation, and also wherein is disclosed a single acting traverse and gain controlling mechanism of simple form, to which existing mechanisms can be 50 readily converted and adapted.

The present invention relates to the inventions disclosed in said applications and

is intended to present a simple form of single acting traverse and gain controlling mechanism to which existing mechanism can be readily adapted, although certain features of said invention are of general or 60 broad application and may be employed in connection with winding mechanisms of other types.

In the present application, I have represented the traverse and gain as effected and 65 controlled by take-up of the flexible element, but obviously my invention may be readily adapted to constructions wherein the flexible element is let off, as will be hereinafter more fully set forth.

In order that the principle of the invention may be readily understood, I have chosen to illustrate that embodiment thereof consisting of builder mechanism for ring spinning frames,—that is, a specific application of winding mechanism.

In the drawing,—Figure 1 is a front elevation of one form of builder mechanism for ring spinning frames constituting an embodiment of the invention; Fig. 2 is a view 80 of said mechanism partially in vertical transverse section and partially in end elevation; Fig. 3 is a view in side elevation of a portion of the mechanism shown in Fig. 1, upon an enlarged scale; Fig. 4 is a detail, 85 partially in section and partially in side elevation, of a portion of the mechanism shown in Fig. 3; Fig. 5 is a longitudinal transverse section taken upon the line 5—5 of Fig. 4, and Fig. 6 is a longitudinal section 90 taken through one of the shafts of the apparatus.

In yarn or thread windings mechanism to which my invention relates, the coils of yarn are laid along the yarn receiver by effecting 95 a relatively oscillatory movement of a yarn guide and the yarn receiver along the latter for a portion of its length, which movement is generally called the "traverse"; and the package is built by shifting the path of this 100 relative movement progressively along the axis of the yarn receiver, which shifting is generally termed the "gain." In the formation of such a yarn package, a maximum diameter is reached at a point above 105 the lower end thereof due to the co-operative effect of the traverse and the gain; and a portion of the package from its lower end to such point of maximum diameter is termed the "base"; while the conical form 110

resulting at the other end of the yarn package is termed the "chase," or the "taper"; and its terminus the "nose" of the cop.

My invention provides means whereby the package may be wound and formed with efficiency in a winding or spinning or twisting machine; and particularly in a spinning or twisting machine it furnishes means whereby the tension of the yarn in winding 5 may be well controlled and thereby the lay of the yarn benefited. In the formation of the base of the package the invention provides means whereby the successive layers of yarn may be so laid, one over the other, 10 until the full diameter of the package is secured, that each bottom coil of each layer is laid safely up and above the bottom coil of the preceding layer (assuming the yarn receiver to be upright and the yarn to be 15 wound thereon from the bottom upward as in the preferred arrangement of parts of mechanism embodying my invention); and while the mechanism accomplishes this broadly in the formation of the base of the package, it may be arranged to continue the 20 same winding effect throughout the entire length of the package. This feature of the winding is accomplished by increasing the gain and preferably by progressively in- 25 creasing the gain throughout the formation 30 of the base of the package; throughout the remainder of the package, the gain should be such as to maintain the body of the package of substantially uniform diameter. To 35 this end, I may, while constantly increasing the traverse throughout the cop, so control the gain as to accomplish this result. This may be effected by providing for an unincreased gain throughout the body of the 40 package above the base, provided the in- 45 creasing traverse be maintained. Coöperatively with this mechanism for increasing the gain, mechanism is provided to increase the traverse throughout the formation of 50 the base and preferably throughout the for- 55 mation of the whole package. The result of this increase of traverse is obviously to lay each successive layer of yarn over a slightly greater extent axially of the package; 55 and further, due to the constant speed of the spindle or other yarn receiver, and in ring frames particularly, due further to the constant speed of the feed rolls, if each traverse is effected in the same period of 60 time (which is accomplished by giving the primary controller of the traverse movement a stroke constant in time and distance), the yarn each time will be laid in coils a little more widely separated. Having 65 reference to the utilization of such a yarn package which involves its unwinding features, the result is that the increasing traverse from base to nose gives reversely a decreasing taper from nose to base, so 70 that the yarn withdrawn by draft axially

of the package is drawn from a surface on the package approaching more and more nearly to a surface at right angles to the axis of the package. By this means, as the length of yarn extending from the surface 70 wherefrom it is being delivered to the point above the package where draft is being applied to the yarn tends to increase, and ballooning of the yarn away from the axis of the package tends to increase, this tendency 75 to increased ballooning effect is checked by the yarn drawing from a surface which tends to approach more and more nearly to a flat surface at right angles to the axis of the package; and when the yarn package is in a shuttle this described construction of package checks the tendency of the yarn 80 to balloon out and contact with the sides of the shuttle, and therefore tends to decrease breakage. Further, as the base of the cop is reached in the unwinding (and throughout the whole package if and when the increase in gain is established throughout the 85 whole package) each bottom coil of each layer (having been safely laid by means of the increase in gain over and above the bottom coil of the preceding layer) is permitted to be withdrawn without fouling with and tending to slough off the preceding layer. These advantages thus secured in the 90 unwinding are of great practical importance in weaving where the yarn is subjected to quick intermittent draft reaching a speed of from five to ten yards a second.

Referring more particularly to the drawings, the builder element herein shown is a cam, as indicated at 2, in Fig. 1, it being fast upon a shaft 1 supported upon the framing and driven at a preferably constant speed in the direction of the arrow 100 thereon, from any suitable mechanism, such, for example, as a worm shaft itself driven by sprocket gearing from the main drive shaft of the spinning frame. I am enabled, because of my invention, to drive the shaft 105 1 and cam 2 at a higher rate of speed than heretofore without changing the speed at which the drawing or feed rolls and the spindles are driven, and therefore to impart more rapid traverses to the ring rail 110 without, however, changing the speed of the spindles, which are preferably driven by bands from the drum, and hence independently of the ring rail.

As will be more fully disclosed herein- 115 after, when I employ that type or form of builder element herein shown, I rotate the same at such speed as to impart thereto a single complete rotation during a single complete traverse of the ring rail or the 120 equivalent mechanism, instead of, as heretofore, rotating the builder cam but a partial revolution for each complete traverse of the ring rail.

The spindle rail is represented at 3, the 130

- spindles at 4, the ring rail at 5, the spinning rings at 6 and the box rail or frame of the spinning frame at 7. These parts are preferably of usual formation and construction, the spindles being continuously rotated in one direction, preferably by bands from the usual drum, and the yarns being delivered thereto by the usual sets of drawing rolls, not shown.
- 10 Suitably mounted in the frame of the machine upon a stud or pivot 8 is a builder lever 9, preferably having a member 10 relatively adjustable with respect thereto by set screw or otherwise, as indicated at 11 and having a roll 12 engaging the periphery of the builder element 2. It will be observed that the builder lever 9, 10 is mounted to rock in a plane extending longitudinally of the frame, and this construction is 15 preferably employed where the parts operate by take-up of the flexible element. I may, however, provide a lever mounted to swing in a plane transverse to the frame, and particularly if the parts operate by letting off of the flexible element.
- Suitably mounted in the frame of the machine, and as herein shown in a bracket 13, is a bell crank lever 14 having an arm 15 upon which rides the lower end of the 20 poker arm or rod 16 depending from the ring rail 5'. The lever 14 is provided with an upwardly extending arm 17, to the outer end of which is suitably secured one end of a flexible connection here shown as a 25 plurality of chains 18. These chains are herein represented as arranged in pairs, and a suitable number of sprocket chains, bell crank levers and poker arms or rods are provided to impart a steady up and down 30 movement to the ring rail 5, and preferably a ring rail and a row of spindles are arranged at each side of the spinning frame.
- In building the yarn package, the yarn is laid upon the receiver in a series of nested 35 cones, each of which is formed during a traverse of the ring rail. In order that these traverses may extend along or with suitable relation to the receiver, an incremental gain is imparted to the traversing mechanism, 40 preferably between the successive traverses. In the present embodiment of the invention, both the traverse and the gain are effected through the chain or other flexible connection or connections 18. Herein, each chain 18 is 45 represented as attached fixedly at one end to the arm 17 of the lever 14, and the other end thereof is connected as hereinafter disclosed to a governing device carried by the builder lever 9, 10. The longitudinal pull imparted 50 to the chains 18 by the builder element 2 rocks the bell crank lever 14 through arcs, the angular extent and position whereof are modified, as hereinafter set forth, by mechanism acting upon said chains 18 between the ends thereof, to effect the laying 55
- of the yarn by traverses which are maintained undiminished and preferably have a regular uniform increase, and by a gain which is also maintained undiminished and which preferably progressively increases 70 throughout at least the base of the package. The bell crank lever 14 having arms 15, 17, I have herein termed the "ring rail lifting means", for convenience of description. Such form of lifting means may be varied 75 within the scope of my invention.
- In order to secure a traverse and a gain of the character above indicated, I have provided adjunctive means co-operating with the builder lever and connections therefrom and 80 which may be varied within the scope of my invention, but which are preferably such that the invention may be readily applied to existing types of ring spinning frames, inasmuch as an important object of the invention is to provide a mechanism of exceedingly simple character for the purpose stated, and which may be adapted to existing types of ring spinning or other winding frames, with comparatively little change. 85
- Herein for the purpose I have mounted upon the box rail 7 a bracket 19 indicated most clearly in Fig. 2, and upon the upper end thereof have mounted upon a pivot or stud 20 a lever 21 having at its lower end a toothed segment 22 meshing with a gear 23 loose upon a shaft 24 mounted in an upward extension 25 of the builder lever 9, 10. The gear 23 is provided with a hub 26 extending through the bracket 19 (which is 90 suitably recessed to permit the described rocking of the builder lever 9, 10 and parts carried thereby), and fast upon said hub is a disk 27 carrying a pawl 28 adapted to engage the teeth of a ratchet 29 shown most clearly in Fig. 3 and fast upon the shaft 24. The said ratchet 29 is adapted, when intermittently actuated by the pawl 28, to impart a step-by-step rotation to the shaft 24. Upon a sleeve 26' of the extension 25 is a 95 casing 30 partially surrounding the ratchet 29, as indicated in Fig. 3, and providing means whereby the pawl 28 engages the ratchet only at or near the end of each movement of oscillation of the segment 22. 100
- It will be observed that with the pick mechanism arranged as shown, a pick takes place while the ring rail is completing the last portion of its up traverse; although my invention is not limited to such mechanism 105 nor the described time of its operation. Since the pick mechanism in the present embodiment of the invention effects both the traverse and the gain, it results that not only is the incremental increase in gain added 110 just at the time when the ring rail is completing the up portion of its traverse, but also since increase in the traverse increases the general speed of the ring rail during the traverse, it follows that the traverse is speed- 115
- 120
- 125
- 130

ed up just as the ring rail is completing its up-stroke. These two factors coöperate in the operation of the mechanism to secure the proper laying of the yarn by tending, first, 5 to keep the coils of each traverse laid well above each other at the top, and second, to reduce the number of coils laid at the top,— that is, when the yarn is being wound upon that portion of the receiver that is of the 10 smallest diameter, and hence when yarn breakage is most apt to occur. The number of coils laid at the top portion of each traverse is reduced in the manner described, inasmuch as the number of coils laid at any 15 portion of the yarn package varies directly as the speed of the ring rail in traversing each portion of the package. Moreover, such number of coils is further reduced when I employ that type of builder element represented in Fig. 1, as will be hereinafter 20 more fully set forth. The described increase in the speed of the ring rail at the upper portion of each traverse not only tends to compensate for the inherent tendency of a 25 ring spinning mechanism to lay more winds of yarn at the upper portion of each traverse, but it also tends to compensate for the lag of the traveler at the upper portion of the up-stroke of the ring rail, and therefore 30 results in less variation of the speed of the traveler due to this lag at the up-portion of its stroke; and not only tends to reduce causes affecting the yarn breakage, but tends to produce a yarn package wound with more 35 uniform tension throughout.

The lever 21 carrying the segment 22 may be oscillated in any suitable manner, but preferably by movement of the builder lever 9, 10. Herein for the purpose, I have provided the builder lever with the arm 25 (or 40 may mount such arm upon the rock shaft 8 co-axially with the builder lever 9, 10). At its upper end, the arm 25 is provided with a lateral extension 31. The lever 21 extends 45 upwardly beyond its pivot 20, as indicated in Figs. 2 and 3, and is there provided with an open slot 32 receiving a bolt 33 extending through the lever 21 and extension 31. The relation of the segment 22 and gear 23 50 may be varied in any suitable manner.

Vertically mounted in the arm 25 is a threaded shaft or screw 34, shown most clearly in Fig. 4, and fast thereon is a beveled gear 35 meshing with a beveled gear 36 55 fast upon the shaft 24. Held from turning upon said screw 34 is a nut 37, which, at the commencement of the building of the cop, is at or near the lower end of the screw 34 and is then gradually elevated by the rotation of the screw from the shaft 24. The nut 37 has loosely mounted therein a stud shaft 38 extending through and projecting at both sides from said nut and having fast upon its ends a pair of eccentrics, here 60 shown as scroll cams 39, 39'. The ends of 65

the flexible connections or chains 18 are fixedly attached to the surfaces of said scroll cams by bolts or otherwise, as indicated at 40, 40' in Fig. 5. Fast upon the stud shaft 38 is a pinion 41 meshing with a rack 42 70 upon the inner face of a portion of the extension 25. Therefore, the outward travel of the nut from the fulcrum of the lever 9, 10 results in a slow rotation of the scroll cams 39, 39' in the direction of the arrow 75 in Fig. 4. Preferably the contour of the scroll cams 39, 39' is substantially such as indicated and may be such as to impart any desired character of gain to the yarn package. Preferably, it is such, that throughout 80 at least the base of the yarn package, a progressively increasing gain is imparted, though within the scope of my invention, any other desired character of gain may be imparted, as, for example, a progressively 85 decreasing or other decreasing character of gain. Preferably, however, the contour of said scroll cams is such as to maintain the gain undiminished throughout at least the winding of the base of the package. The 90 gradual elevation of the nut 37 and consequent change in position of the chains 18 effects a constant increase in the traverse. In the present embodiment of the invention, the pick mechanism is constant or unvarying in operation, this being an important 95 feature of the invention and one preferably employed, inasmuch as by employing a pick mechanism of the character indicated, I greatly simplify the construction of parts. 100 Owing to the described character of pick mechanism, the movements of the nut 37 upon the screw 34 are uniform. The gradual rotation of the scroll cams 39, 39' effects, in the embodiment of the invention 105 shown, a progressive increase in the gain throughout at least the base of the package, because the described movement of the nut 37 outward or away from the fulcrum of the builder lever 9, 10 shortens by progressively 110 increasing increments the distance between the point of attachment of the chains 18 to the arm 17 of the bell crank lever and the scroll cams 39, 39' measured along the shortest line. Moreover, inasmuch as when the 115 ring rail 5 is in its lowermost position, the arm 15 of the bell crank lever is somewhat below, and is moving toward the horizontal, it follows that the linear movements imparted by the arm 15 to the poker arm or rod 16 120 gradually increase in length due to the movement of said arm 16 upwardly toward the horizontal, in analogy to the increased linear movements imparted by a crank when approaching the horizontal. Such increased 125 linear movements of the poker arm or rod 16 continue throughout the formation of the base of the yarn package at least. Moreover, the slow rotation of the scroll cams 39, 39', by progressively presenting to the 130

chains 18, 18 portions of said scroll cams at increasingly greater radial distances from the stud shaft 18, supplements the outward movement of the nut 37 and changes the 5 traverse from a regularly increasing traverse to a progressively increasing traverse. Obviously, however, the character of the traverse in this respect may be modified by varying the contour of the scroll cams 39, 39'.

10 In the present embodiment of the invention, the several factors set forth combine to effect a progressively increasing gain throughout the formation of the base of the 15 yarn package, and the continued movement of the arm 15 is not thereafter such as substantially to modify the character of the gain during the further formation of the 20 yarn package.

Although I have referred to the increase 25 in the traverse as constant, it will be understood that thereby is meant a regular or periodic increase, inasmuch as in practice the traverse is not increased at all instants of time during the operation of the mechanism, but preferably only at a certain period or 30 part of each traverse.

After the nut 37 has been elevated by rotation of the screw 34 in the building of the 35 yarn packages, the said nut is returned, preferably by hand, for the formation of the next set of yarn packages. Herein for the purpose I have provided the shaft 24 with a crank handle 43, shown in Fig. 3, so that by rotation of said shaft and of the 40 screw 34, the nut 35 may be lowered to the desired extent.

It will be understood from the foregoing 45 description that the effect of the travel of the nut 37 upon the chains 18 is such that the arcs of movement of the builder lever 9, 10 not only gradually increase in length, providing the gradually increasing lengths 50 of conical layers, but the said arcs of movement are gradually advanced contraclockwise so that the rods or poker arms 16 descend to an incrementally higher point, after each upward portion of the traverse, thus 55 providing a gain which, as previously stated, is progressively increased.

50 In employing the term "traverse", I mean a complete forward and return movement of the yarn guide or complete forward or relative return movement of the same with respect to the yarn receiver. Each return 55 movement terminates at a distance above the commencement of the traverse measured by the extent of the gain.

60 Preferably I form each traverse as a vibratory traverse, by which I mean a traverse consisting of a series of advances and retrogressions. To accomplish this result, I may provide any suitable mechanism, but herein I have represented the builder element 2 as a cam having a series of faces a , a' , b , b' , c , c' , d , d' , e , e' . The cam 2 travels

in the direction of the arrow thereon and at such a speed that it completes one revolution during a single complete traverse. Considering the first or any complete traverse, while the face a is acting upon the 70 roll 12, the yarn guiding means is moved upwardly to such an extent as to lay the yarn in an open wind to a height reaching but part way to the ultimate height of the said traverse. Thereupon, the face a' becomes active and the yarn is returned in an 75 open wind to a point slightly above the commencement of that traverse. Thereupon the face b becomes active and the yarn is laid in an open wind to a point slightly higher than that reached when the face a was active. Thereupon the face b' becomes 80 active and the yarn is laid in an open wind downwardly to a point slightly above that reached when the face a' was active. Thereupon the face c becomes active and the yarn 85 laid in an open wind to a point slightly above that reached when the face b was active, such point being the most advanced point reached during the laying of that 90 traverse. Thereupon the face c' becomes active and the yarn is laid in an open wind downwardly to the point reached when the face b' was active. Then the face d becomes active, and the yarn is laid upwardly in an open 95 wind to the point reached when the face b was active. Then the face d' becomes active, and the yarn is laid downwardly in an open wind to the point reached when the face a' was active. Then the face e becomes active 100 and the yarn is laid upwardly in an open wind to the point reached when the face a became active, and then the face e' becomes active and the yarn is laid downwardly in an open wind to a point short of the point 105 where the entire traverse commenced, by a distance equal to the extent of the gain.

Within the scope of my invention, the 110 lengths of the faces of the builder cam 2 may be varied, so that any step or portion of a single traverse terminates at the same height as any other step or portion of the traverse or at a height differing from that reached at any other step or portion of the traverse. I have secured excellent results 115 by providing the cam 2 with faces a , a' together equaling $67\frac{1}{2}^\circ$, with faces b , b' equaling $67\frac{1}{2}^\circ$, with faces d , d' equaling $67\frac{1}{2}^\circ$, and with faces c , c' each equaling 45° . The several faces may be of unequal length, so as to 120 prevent any portion of the traverse terminating coincidentally with any other portion thereof.

If desired, there may be an unequal number of vibratory movements on the two parts 125 of each traverse; as for example there may be three vibratory movements on the up portion of the traverse, and two vibratory movements on the down portion of the traverse. This may be effected by suitably 130

shaping the cam 2 or in any other desired manner. The number of vibratory movements may, of course, be any other than those herein indicated.

Referring to the vibratory traverse mechanism and its coöperation with the pick mechanism, I preferably provide a construction such as shown whereby the pick mechanism is actuated to cause a gain or advance of the ring rail only once for each traverse irrespective of the vibratory movements given the ring rail during the main traverse. In the mechanism as shown, the pick mechanism is so constructed and arranged as to advance the ring rail at the latter end of the upward stroke of the main traverse, the pick pawl being prevented from engaging with the ratchet during any portion of the main traverse except at such time. Co-operatively, the cam to give the vibratory traverse is so arranged that only one of the vibratory movements takes place in a manner to actuate the pick mechanism; that is, as shown in Figs. 1 and 3, the pick has been given in the last few degrees of rotation of the cam prior to the passage of the point B over the roll 12; and after the passage of such point and before the cam has moved so that the portion of the cam α has passed over the roll, the ring rail has been lowered so that the pick pawl has been engaged and lifted by the shield 30, and thereafter during the remaining vibratory movements of the ring rail the pick pawl remains so disengaged.

The form of pick mechanism shown accomplishes the desired objects with a very simple arrangement of parts, but I am not limited thereto.

Inasmuch as each traverse is increased over its predecessor, each traverse advances more at the top of the wind than at the bottom thereof. The effect of the described traverse and gain are to build a yarn package, which at the bottom extends from the surface of the receiver to a maximum diameter without laying the bottom coil of any wind or traverse on top of or below the bottom coil of the preceding layer or traverse. The slight but continuous incremental increase in the gain throughout at least the base of the package, together with a direct increase in the traverse, lays the yarn so uniformly that the chase of the yarn package is formed with a straight line constituting a conical bottom in vertical cross section until the maximum diameter of the cop or other yarn package is reached. Such maximum diameter is substantially maintained until the tip of the yarn package is reached. Thus, the increase in traverse and incremental increase in gain are effective to produce and maintain a correct and advantageous form of package. While I have referred to the increase in the traverse as con-

stant, this term is employed generically or broadly to refer to a preferably regular increase in the traverse, such increase occurring at a certain part of each traverse, or, if desired, at a certain part of each of a series of traverses. I preferably impart the increase to the traverse and the increase to the gain during the up-stroke of the ring rail, and preferably near the end of such up-stroke and terminating with the end of the up-stroke. Inasmuch as the builder cam employed in the disclosed embodiment of the invention rotates preferably at a constant speed, and inasmuch as the traverse is regularly increased, it follows that the speed of the ring rail is correspondingly increased, and inasmuch as the addition to the traverse and the addition to the gain are imparted in the present embodiment of the invention at or near the end of the up-stroke of the ring rail, it follows that the speed of movement of the ring rail is accelerated each time toward the end of its up-stroke—that is, when the yarn is winding upon the nose of the yarn package.

As stated above, the precise embodiment of the invention herein shown provides means for controlling the gain and traverse in a form wherein the flexible element is progressively shortened or taken on. Modification of the mechanism to give the same control, *i. e.*, increasing traverse as discussed and generally decreasing gain as discussed, is readily secured by so arranging the outwardly moving builder nut and scroll that the flexible element is released by increasing increments as the builder nut moves outward by uniform increments, being essentially the reverse of the arrangement herein shown. Further the application of the said traverse and gain-controlling mechanism to such forms of builder mechanism as shown in a co-pending application by John V. Cunniff, filed July 1, 1912, Serial No. 706,910, will be readily apparent to those skilled in the art.

After having laid the first traverse in the manner indicated, the second traverse commences at a point above the commencement of the first traverse by a distance equaling the gain and the same operation is repeated throughout the formation of the yarn package. It will be apparent that each traverse is laid in an open cross wind, which is more advantageous for unwinding than the usual wind. It is, of course, obvious that the number of steps into which each traverse is divided may be varied within the scope of my invention, as by providing the cam 2 with a different number of faces from that shown, or in any other suitable manner. Another advantage of the described wind is that I so regulate the decrease in the speed in the winding-on of the yarn upon the portion of the yarn receiver that is of least di-

ameter (and by least diameter I mean the least diameter of that portion of the yarn receiver covered by each traverse of the yarn) that the lag of the traveler as the 5 ring rail moves toward and away from the nose of the yarn package is minimized. Therefore, a more generally rapid movement of the ring rail per minute may be effected, so that with an assumed spindle 10 speed and an assumed ring rail speed, a more open lay of the wind will be accomplished. I have previously stated that the lag of the traveler is diminished by increasing the ring rail speed, inasmuch as fewer 15 turns of the yarn are laid at the upper end of each traverse. It will be evident that by laying the yarn as an open wind, the number of turns is further lessened, thus still further minimizing the lag of the traveler. 20 Having thus described one illustrative embodiment of my invention, I desire it to be understood that although specific terms are employed, they are used in a generic and descriptive sense and not for purposes of 25 limitation, the scope of the invention being set forth in the following claims.

Claims:

1. A traverse motion for winding yarn on yarn receivers, comprising in combination 30 rotatable spindles, a ring rail, a rotatable builder element, a building lever and a ring-rail-rod engaging lever both mounted to oscillate in planes lengthwise of the ring frame, said builder lever having two arms, 35 one adapted to be acted upon by said builder element and the second arm extending upwardly toward the ring rail, a flexible element having one end fixedly connected to said ring-rail-rod engaging lever, a rotatable scroll carried by said upwardly extending arm of the builder lever and to which the other end of said flexible element is connected.

2. In a traverse motion for winding yarn 45 on yarn receivers, a rotating yarn receiver, yarn guiding means coöperating with the receiver, a builder element, a builder arm 50 acted on by said builder element, a flexible connection between and flexibly associated with said yarn guiding means and said builder arm, and by the movement of which by said builder element a series of traverse movements is imparted to said yarn guiding means, means active upon said flexible 55 connection at its portion operatively associated with the builder arm to effect, through said flexible connection, an increasing shift or gain of the traverse movement along the yarn receiver throughout the formation of the base 60 of the package, and an increasing traverse movement throughout the package, means incrementally to lift said active means and the adjacent portion of the flexible connection toward said yarn receiver in effecting said gain and traverse, and means to

rotate said means active upon the flexible connection, thereby to present successive portions thereof to said flexible connection.

3. In a traverse motion for winding yarn on yarn receivers, a rotatable yarn receiver, 70 yarn guiding means coöperating with said receiver, a builder element, a builder member acted upon by said element and having a portion extending in a direction toward said yarn receiver, a flexible connection between and operatively associated with said yarn guiding means and said builder member and by the movement of which by the builder element a series of traverse movements is imparted to said yarn guiding 75 means, and means upon said portion of said builder member to effect through said flexible connection an increasing shift or gain of the traverse movements along the yarn receiver throughout the formation of the base 80 of the package and an increasing traverse movement throughout the package, and including a rotary member.

4. In a traverse motion for winding yarn on yarn receivers, a rotating yarn receiver, 90 yarn guiding means coöperating with the receiver, a builder element, a builder lever having two angularly related arms upon one of which said builder element is adapted to act, the other arm extending toward 95 the yarn receiver, a flexible connection between and operatively associated with said yarn guiding means and with the said other arm of said builder lever and by the movement of which flexible connection by the builder element, a series of traverse movements is imparted to said yarn guiding means, means upon said second arm of the builder lever and active upon said flexible connection to effect throughout said flexible 100 connection an increasing shift or gain of the traverse movement along the yarn receiver throughout the formation of the base of the package, and an increasing traverse movement through the package, and means to rotate 105 said means active upon the flexible connection, thereby to present successive portions of its surface to the flexible connection.

5. In a traverse motion for winding yarn 115 on yarn receivers, a continuously rotating yarn receiver, yarn guiding means coöperating with the receiver, a builder element, a builder lever having two angularly related arms upon one of which said builder element 120 is adapted to act, the other arm extending toward the yarn receiver, a flexible connection between and operatively associated with said yarn guiding means and with the said other arm of said builder lever and by the 125 movement of which flexible connection by the builder element, a series of traverse movements is imparted to said yarn guiding means, means upon the second arm of said flexible connection and movable therealong 130

toward the yarn receiver, and to which means one end of said flexible connection is attached, and means to rotate said means active upon the flexible connection and to move it along said second arm of said builder lever.

6. In a traverse motion for winding yarn on yarn receivers, a rotating yarn receiver, yarn guiding means coöperating with the receiver, a builder element, a builder lever having two angularly related arms upon one of which said builder element is adapted to act, the other arm extending toward the yarn receiver, a flexible connection between and operatively associated with said yarn guiding means and with the other arm of said builder lever and by the movement of which flexible connection by the builder element, a series of traverse movements is imparted to said yarn guiding means, means upon the second arm of said builder lever and movable therealong toward said yarn receiver, and to which means one end of said flexible connection is attached, said means active upon the flexible connection having an eccentric surface, and means to rotate said means active upon the flexible connection, thereby to present successive portions of such eccentric surface to the flexible connection and to move it along said second arm of the builder lever.

7. In a traverse motion for winding yarn on yarn receivers, a rotating yarn receiver, yarn guiding means coöperating with the receiver, a builder element, a builder lever having two angularly related arms upon one of which said builder element is adapted to act, a flexible connection between and operatively associated with said yarn guiding means and with the other arm of said builder lever and by the movement of which flexible connection by the builder element, a series of traverse movements is imparted to said yarn guiding means, means upon the second arm of said lever and active upon the flexible connection, said flexible connection having a portion which in its lowermost position extends substantially horizontally from its point of attachment with the yarn guiding means to said means active upon said flexible connection, means to move said means active upon the flexible connection along said lever arm, thereby to elevate said horizontal portion of the flexible connection, and means to rotate said means active upon such connection.

8. In a traverse motion for winding yarn on yarn receivers, a continuously rotating yarn receiver, yarn guiding means coöperating with the receiver, a poker arm having operative connection with the yarn guiding means, a bell crank lever engaging said poker arm, a builder element, a builder lever having two angularly related arms, upon one of

which said builder element is adapted to act, 65 and the second of which extends upwardly, a flexible connection between and operatively associated with said bell crank lever and with the said second arm of said builder lever and by the movement of which flexible 70 connection by the builder element, a series of traverse movements is imparted to said yarn guiding means, means upon said second arm of the builder lever and active upon said flexible connection between its ends and 75 to which one end of the latter is attached, and means to rotate said means active upon the flexible connection.

9. In a traverse motion for winding yarn on yarn receivers, a rotating yarn receiver, 80 yarn guiding means coöperating with the receiver, a builder element, a builder lever having two angularly related arms upon one of which said builder element is adapted to act, and the second of which extends toward 85 the yarn receiver, a flexible connection between and operatively associated with said yarn guiding means and with the said second arm of said builder lever and by the movement of which flexible connection by 90 the builder element, a series of traverse movements is imparted to said yarn guiding means, means upon said second arm of the builder lever and active upon said flexible connection and to which one end of the latter 95 is attached, and means to rotate said means active upon the flexible connection.

10. In a traverse motion for winding yarn on yarn receivers, a rotating yarn receiver, 100 yarn guiding means coöperating with the receiver, a builder element, a builder lever having two angularly related arms upon one of which said builder element is adapted to act, and the second of which extends toward 105 the yarn receiver, a flexible connection between and operatively associated with said yarn guiding means and with the said second arm of said builder lever and by the movement of which flexible connection by 110 the builder element, a series of traverse movements is imparted to said yarn guiding means, means upon the second arm of said builder lever active upon said flexible connection, a nut and screw to move said 115 means along said arm, and means to rotate said means active upon the flexible connection.

11. A traverse motion for winding yarn on yarn receivers, comprising in combination rotatable spindles, a ring rail, a rotatable 120 builder element, a builder lever and a ring-rail - rod engaging lever both mounted to oscillate in planes lengthwise of the ring frame, said builder lever having two arms, one adapted to be acted upon by said builder 125 element and the second arm extending upwardly toward the ring rail, a flexible element having one end fixedly connected to

said ring-rail-rod engaging lever, a rotatable scroll carried by said upwardly extending arm of the builder lever and to which the other end of said flexible element is connected, said scroll having an eccentric surface.

12. A traverse motion for winding yarn on yarn receivers, comprising in combination rotatable spindles, a ring rail, a rotatable builder element, a builder lever and a ring-rail-rod engaging lever both mounted to oscillate in planes lengthwise of the ring frame, said builder lever having two arms, one adapted to be acted upon by said builder element and the second arm extending upwardly toward the ring rail, a flexible element having one end fixedly connected to said ring-rail-rod engaging lever, a rotatable scroll carried by said upwardly extending arm of the builder lever and to which the other end of said flexible element is connected, and means including a nut and screw to move said scroll along said upwardly extending arm of the builder lever and to rotate the scroll.

13. In a traverse motion for winding yarn on yarn receivers, a rotatable yarn receiver, yarn guiding means coöperating with said receiver, a builder element, a builder member acted upon by said element and having a portion extending in a direction toward said yarn receiver, a flexible connection between and operatively associated with said yarn guiding means and said builder member and by the movement of which by the builder element a series of traverse movements is imparted to said yarn guiding means, means upon said portion of said builder member and active upon said flexible connection, means to move said active means along said portion of said builder member, and means whereby to present different por-

tions of said means to said flexible connection during the winding operation.

14. In a traverse motion for winding yarn on yarn receivers, a rotating yarn receiver, a ring rail, ring rail lifting means, a builder element, a builder arm acted on by said element, and having an upwardly extending portion, a flexible connection attached to said ring rail lifting means and connected to said arm, a nut movable by increments along said upwardly extending portion of said arm and rotatable means movable with said nut and active upon said flexible connection, thereby to present successive portions of its surface to said flexible connection and to lift the entire portion of said flexible connection between said nut and said ring rail lifting means and thereby to effect traverse and gain.

15. In a traverse motion for winding yarn on yarn receivers, a rotating yarn receiver, a ring rail, ring rail lifting means, a builder element, a builder arm acted on by said element, and having an upwardly extending portion, a flexible connection attached to said ring rail lifting means and connected to said arm, a nut movable by increments along said upwardly extending portion of said arm, rotatable means movable with said nut and having an eccentric surface active upon the flexible connection to lift the entire portion of said flexible connection between said nut and said ring rail lifting means and thereby to effect traverse and gain.

In testimony whereof, I have signed my name to this specification, in the presence of two subscribing witnesses.

JAMES K. LANNING.
